United States Patent Office

Des. 229,330
Patented Nov. 20, 1973

229,330

WHEEL CHOCK

Ray P. Miles, Macedonia, Ohio, assignor to Copperloy Corporation, Independence, Ohio

Filed Oct. 6, 1971, Ser. No. 187,215

Term of patent 14 years

Int. Cl. D12—05

U.S. Cl. D41—1 C

Fig. 1

Fig. 2

FIG. 1 is a perspective view of a wheel chock embodying the invention; and

FIG. 2 is a bottom view thereof.

The side is lined for light red on the lower half and dark red on the upper half.

The side and end not visible in the drawings are the same in structure and appearance as the side and end shown, respectively.

I claim:

The ornamental design for a wheel chock, as shown and described.
